4 Claims. (Cl. 235—156)

This invention relates generally to computing apparatus and more particularly to a hybrid arithmetic unit which performs operations on a mixture of analog and digital quantities.

When dealing with computers, most people think in terms of either analog or digital computers. Each type has certain advantages and disadvantages when handling mathematical problems. Certain classes of problems, such as those found in industrial process control applications or in the solution of differential equations, may be more neatly solved by a combination of analog and digital techniques.

A hybrid computer is a digital computer having an auxiliary arithmetic unit which performs its digital operations by analog methods. The question may arise as to why anyone would want to use an arithmetic unit that performs its operations in an analog manner since analog computation does not incorporate the accuracy which is inherent in digital techniques. The answer to this question is very simple since very often speed and flexibility of computation are important whereas some inaccuracies of computation may be allowable. By the use of a hybrid arithmetic unit, many computations needed in certain problems can be performed at speeds not obtainable with comparable amounts of equipment using solely digital techniques. Hybrid arithmetic techniques also offer flexibility which is not obtainable with digital techniques. Because of the analog nature of such a hybrid arithmetic unit, it will also perform operations on a mixture of analog and digital quantities.

Therefore, it is the principal object of this invention to provide a hybrid arithmetic unit capable of performing computations with both digital and analog input signals.

An important object of this invention is to interconnect the components of a hybrid arithmetic unit by digitally controlled multiplexers so that various computations may be made in an analog manner.

It is another object of this invention to provide an analog arithmetic unit for use in combination with a digital computer.

Still another object of this invention is to provide a hybrid arithmetic unit which operates on digital information in an analog manner to provide an analog output which is a desired arithmetical function of the digital input.

A more specific object of this invention is to provide a hybrid arithmetic unit for operating on a mixture of digital and analog quantities in an analog manner to provide an analog output which is converted to digital form.

Briefly, the foregoing and other objects are accomplished by a plurality of digital-to-analog converters each providing an analog output which is proportional to the product of a digital input signal and an analog input or reference signal. Plural analog signal sources may be selectively connected to the inputs of the converters through digitally controlled switches or multiplexers. Furthermore, the analog input signal for any given digital-to-analog converter may be derived from the analog output of another digital-to-analog converter whose output is also proportional to the product of its own digital input and analog reference signal. Therefore, a combination of two digital-to-analog converters may perform the multiplication of two digital inputs in an analog manner. Additionally, two digital-to-analog converters may be connected in a common output circuit across which is developed a

resultant analog voltage which is proportional to the sum of the digital inputs to the converters. Digitally operated multiplexers provide such arrangements with great flexibility and speed in changing from one type of computation to another. The digital input and control signals may be provided by a digital computer.

Other objects of the invention will be pointed out in the following description and claims and illustrated in the accompanying drawings which disclose, by way of example, the principle of the invention and the best mode which has been contemplated of applying that principle.

In the drawings:

FIG. 1 is a schematic diagram of a specific digital-to-analog converter circuit;

FIG. 2 is a block diagram of a digital-to-analog converter;

FIG. 3a is a block diagram of a summing amplifier;

FIG. 3b is a more detailed diagrammatic representation of a summing amplifier;

FIG. 4 is a block diagram of a digitally controlled multiplexer;

FIG. 5 is a block diagram of a digitally variable gain amplifier;

FIG. 6 is a block diagram of a comparator;

FIG. 7 shows two digital-to-analog converters feeding a comparator;

FIG. 8 is a logical block diagram for summing two products;

FIG. 9 is a logical block diagram for multiplying two digital quantities;

FIG. 10 is a block diagram of a hybrid arithmetic unit embodying this invention;

FIGS. 11 and 12 show interconnections of the components of the hybrid unit for performing specific computations; and

FIG. 13 shows the incorporation of such a hybrid unit in the auxiliary arithmetic unit of a programmed digital computer.

The analog output of a digital-to-analog converter is proportional to the product of an analog reference and the digital input. The reference can be produced by a second digital-to-analog converter, thereby making the first output proportional to the product of both digital inputs and the reference to the second generator. This process can be continued "n" times, thereby making the ultimate output analog proportional to the product of "n" digital inputs. The output can be converted to a digital quantity, thereby making the digital output D_o equal to $D_1 \cdot D_2 \dots D_n$ where $D_1, D_2 \dots D_n$ represent the digital inputs to "n" digital-to-analog converters. This process will be called hybrid multiplication for obvious reasons.

A second important hybrid operation is addition. Assume two digital-to-analog converters have a common output. The output analog then will be proportional to the sum of the two digital inputs, $D_1 + D_2$. If several digital inputs and converters are provided and the output analog is converted to a digital quantity, then the digital output is represented by $D_o = D_1 + D_2 + \dots + D_n$.

In hybrid multiplication, the digital quantities $D_1, D_2 \dots D_n$ are preset and D_o is allowed to vary. If, however, D_o is preset and any of $D_1, D_2 \dots D_n$ is allowed to vary, hybrid division would be effected.

Hybrid subtraction is realized by a similar analogy or by allowing the outputs of the converters to have a negative or bipolar range. Various combinations of the preceding techniques can be effected simultaneously, thereby performing complex arithmetic manipulations in a single operation. Also, since the operations are performed by connecting digital-to-analog converters through a summing amplifier, rearrangement of these connections can be performed with the aid of multiplexing, thereby making it possible to perform many complex arithmetic opera-

tions with one set of converters. Since the multiplexing can be controlled digitally, hybrid computation has great flexibility.

Before describing a hybrid arithmetic unit and the components thereof embodying this invention, we shall first review briefly the technique of converting digital information to analog information. In FIG. 1, there is shown an example of a unipolar, three binary bit, digital-to-analog converter. The converter comprises four resistors 10, 12, 14 and 15 having relative resistance values of 2R, 4R, 8R and 8R respectively. Each resistor is connected at one end thereof to an output terminal 16. The other end of each resistors 10, 12 and 14 is connected to a corresponding movable switch arm 18, 20, or 22 of three single pole, double throw switches designated as representing digital, binary units D_1 , D_2 , and D_3 , respectively. Associated with each switch is a grounded terminal 24, 26 and 28, respectively. The other terminal 30, 32 or 34, respectively, of each switch, is connected to a conductor 36 which in turn is connected to a reference voltage V_r represented by a battery 40. Resistor 15 is permanently connected between output terminal 16 and ground.

The position of the switches D_1 , D_2 , D_3 represents a binary digital input. Each switch is always in one of its two positions, i.e., connected to its associated ground terminal or else to the reference voltage through conductor 36.

As an example of the operation of the digital-to-analog converter of FIG. 1, let us assume a digital input of 2⁰ or in binary terms, 001. In this case, D_3 is "1," D_2 is "0" and D_1 is "0." Therefore, switch arm 22 is closed to reference V_r by contact with terminal 34. Switch arms 20 and 18 are connected to ground through their respective terminals 26 and 24. With such an arrangement, it can then be seen that there is formed a series-parallel combination of resistors connected between reference V_r and ground with the analog output being taken across the parallel network of resistors. More specifically, resistor 14 is connected in series with a parallel combination of resistor 12, resistor 10 and resistor 15. It can then be determined by simple network analysis that the output voltage V_o is equal to $V_r/8$. By the same method of analysis, it can be determined that when D_2 is "1" and D_1 and D_3 are "0's," output voltage V_o is equal to $V_r/4$, and when D_1 is closed to the reference voltage and the other switches grounded, V_o is equal to $V_r/2$. The digital inputs represent in the order described the decimal numbers 1, 2 and 4 and it can be seen that the analog outputs are in the same ratios. It can be shown that other combinations of D_1 , D_2 , D_3 will cause V_o to vary from zero to $7/8V_r$ in steps of $V_r/8$.

The digital-to-analog converter of FIG. 1 may be analyzed in more general terms. The switches representing the binary digital inputs D_1 , D_2 and D_3 can be thrown individually to zero (ground) volts or V_r volts with ground being a logical "0" and V_r volts being a logical "1." This circuit may be analyzed by the use of Thevenin's theorem. The output impedance of FIG. 1 with all the switches closed to reference V_r is

$$(1) \quad R_{out} = R$$

The short circuit current is

$$(2) \quad I_{sc} = \frac{V_r D_1}{2R} + \frac{V_r D_2}{4R} + \frac{V_r D_3}{8R}$$

where D_1 , D_2 and D_3 are independent logical "1's" or "0's." The open circuit voltage V_{oc} is equal to the short circuit current I_{sc} multiplied by the output impedance R_{out} or

$$(3) \quad V_{oc} = I_{sc} \cdot R_{out} = (4D_1 + 2D_2 + D_3) \frac{V_r}{8}$$

It should be noted that the bracketed factor in Equation 3 is the definition of a binary number, where D_1 is the most significant bit, D_2 is the next significant bit and D_3

is the least significant bit. Furthermore, Equation 3 illustrates that the open circuit voltage V_{oc} is not only proportional to the digital input D , but it is also proportional to the analog reference voltage V_r . The proportionality of the analog output voltage to both the analog reference and the digital input is very important for the understanding of the operation of the hybrid digital/analog arithmetic unit. This proportionality may be expressed as

$$10 (4) \quad V_{oc} \sim D \cdot V_r$$

where D is the digital input D_1 , D_2 , D_3 .

In FIG. 2, there is shown a block diagram form of a digital-to-analog converter which may be of the type illustrated in FIG. 1. In FIG. 2 and throughout the remainder of this specification, digital information will be connected to the tops of the blocks and analog information will be connected to the sides of the blocks. Consequently, in FIG. 2, a digital input D (where $D=D_1$, D_2 , D_3) is applied to the top of the block 44 designated D/A representing a digital-to-analog converter. The analog reference voltage A is applied to the left hand side of D/A, and the analog current output B is shown as leaving block 44 at the right hand side thereof.

Digital/analog building blocks

There will now be described several digital/analog building blocks which are the components of the hybrid arithmetic unit. The digital-to-analog converter shown in FIG. 2 is of course the basic building block of such a hybrid arithmetic unit. The + sign in block 44 indicates that A and B inputs are unipolar and positive. As mentioned above, D is the digital input D_1 , D_2 , D_3 and A is the reference or analog input while B is the analog current output. The function performed by block 44 is that the analog output B is proportional to the product of the reference voltage input A and the digital input D . For convenience, such a relationship, and similar relationships of proportionality in the following description, will be expressed in equation form as

$$40 (5) \quad B = A \cdot D$$

In FIG. 3a there is shown a conventional summing amplifier 46 having a negative gain ($-K$). Once again A is an analog current input and B is the analog voltage output. The function performed by block 46 is that the analog voltage output B is proportional to the negative of the product of the gain and the analog current input or as expressed in equation form

$$50 (6) \quad B = -K \cdot A$$

FIG. 3b is a more detailed schematic diagram of summing amplifier 46.

Summing amplifier 46 incorporates a conventional chopper stabilized amplifier which sums plural currents from a relatively high impedance source to provide a relatively low impedance output voltage which is proportional to the sum of the input currents. Such an amplifier, therefore, performs the required summing function and also provides the low impedance analog voltage which is required at the input of each digital-to-analog converter. The diagram in FIG. 3b will serve to explain the operation of summing amplifier 46. The analog input currents may be represented by the three input resistors R each having applied thereto a corresponding analog voltage V_1 , V_2 or V_3 . The currents are applied to a chopper stabilized amplifier 43 having a feedback resistor 41 which has a value KR where K is the gain of summing amplifier 46. Such an arrangement results in a highly accurate output voltage which is proportional to the negative of the summed input currents and the gain K of the amplifier.

In FIG. 4 there is shown a block diagram of a multiplexer 45. D represents a single binary bit input in this case whereas A is the analog voltage input and B is the analog voltage output. The function performed by this

block is that the output voltage B is equal to the input voltage A when the digital input D is a "1" and is independent of input voltage A when the digital input is a "0." In other words, multiplexer 43 functions as a switch or gate to control the transmission of analog signals. Such an operation may be expressed in equation form as follows:

$$(7) \quad \begin{aligned} B &= A \text{ when } D=1 \\ B &\neq f(A) \text{ when } D=0 \end{aligned}$$

In FIG. 5 there is shown a block diagram of a variable gain amplifier 47 incorporating a negative gain summing amplifier 48 as shown in FIG. 3 and a digital-to-analog converter 50 as shown in FIG. 2. Variable gain amplifier 47 has a gain which is a function of the digital input D . Once again, A is the analog current input and B is the analog voltage output. The digital-to-analog converter 50 varies the amount of feedback, and consequently the gain, by means of the controlling digital input D . The function performed by amplifier 47 is that the voltage output B is proportional to the negative of the product of the analog current input A and digital input D or in equation form

$$(8) \quad B \sim -A \cdot D$$

FIG. 6 shows a block diagram of a comparator 52 which compares two analog inputs to provide a digital output indicative of the relative magnitudes of the inputs. In this case, A is a positive analog current input and B is a negative analog current input whereas D is a digital output. The function performed by block 52 is that it compares both current inputs A and B and provides a digital output D indicative of which input is the greater in magnitude. This may be expressed in equation form as follows:

$$(9) \quad \begin{aligned} |A| \geq |B| &\text{ then } D=1 \\ |A| < |B| &\text{ then } D=0 \end{aligned}$$

As will be explained in the description of FIG. 7, the digital output D controls the logic of the system with which comparator 52 is associated so that, after the conversion, $|A|=|B|$ to the least significant bit.

Interconnection of building blocks

FIG. 7 shows two digital-to-analog converters 54 and 55 feeding a comparator 58. B_1 is the analog output from converter 54 and B_2 is the analog output from converter 55, B_1 and B_2 each being applied as analog inputs to comparator 58. Digital output P of comparator 58 is also applied to logical circuits represented by the decision logic block whose output E acts in the manner of an error signal to control the sources of A_1 and A_2 in such a manner that the analog quantities B_1 and B_2 become equal. Under this condition

$$(10) \quad A_1 \cdot D_1 = A_2 \cdot D_2$$

If the quantities A_1 , A_2 and D_2 are preset and D_1 is varied until $B_1=B_2$ then Equation 10 can be rewritten as:

$$(11) \quad D_1 = \frac{A_2}{A_1} \cdot D_2$$

If on the other hand, A_1 , A_2 and D_1 are preset and D_2 is varied until $B_1=B_2$, then the Equation 10 becomes

$$(12) \quad D_2 = \frac{A_1}{A_2} \cdot D_1$$

The significance of Equations 11 and 12 is that, depending upon whether D_1 or D_2 is preset, the function A_1/A_2 or its reciprocal may be digitized. In this case, the preset digital input would be set to a value of "1."

FIG. 8 shows a logical block diagram for summing two products. A digital input D_1 and an analog input A_1 are applied to a digital-to-analog converter 60 whose analog current output A_3 is applied to the input of a negative unity gain summing amplifier 62 whose analog voltage output C_1 is proportional to the negative product

70

of A_1 and D_1 . In like manner, digital input D_2 and analog input A_2 are applied to a digital-to-analog converter 64 whose analog output A_4 is applied to the input of a negative gain summing amplifier 66 which provides an analog voltage output C_2 proportional to the negative product of A_2 and D_2 . C_1 and C_2 are converted to currents by resistors 68 and 70 to provide a resultant analog signal A which is applied to the input of another negative unity gain summing amplifier 72 whose analog voltage output B is proportional to the negative of the sum of C_1 and C_2 and, thereby, to the sum of $A_1 \cdot D_1 + A_2 \cdot D_2$. These foregoing functions may be conveniently expressed in equation form as follows:

$$\begin{aligned} (13) \quad C_1 &= -A_1 \cdot D_1 \\ (14) \quad C_2 &= -A_2 \cdot D_2 \\ (15) \quad B &= A_1 \cdot D_1 + A_2 \cdot D_2 \end{aligned}$$

FIG. 9 illustrates a logical block diagram for the multiplication of two digital quantities. As in the previous

cases, a digital input D_1 and an analog reference voltage $+U$ are applied to the input of a digital-to-analog converter 74. The reference $+U$ is equal to positive unity. The analog output A_1 of converter 74 is applied to the input of a negative unity gain summing amplifier 76 whose analog output C_1 is applied to the input of another digital-to-analog converter 78 together with a digital input D_2 . The resulting analog current output A_2 is applied to another negative gain summing amplifier 79 which provides an analog voltage output B proportional to the product of U , D_1 and D_2 or

$$(16) \quad B = U \cdot D_1 \cdot D_2 = D_1 \cdot D_2$$

Hybrid digital/analog arithmetic unit

In the foregoing description, digital/analog building blocks and some simple interconnections of them have been explained. In FIG. 10, there are shown two levels of a hybrid digital/analog arithmetic unit 150 incorporating these building blocks. The unit consists of three sections.

Section I performs the arithmetic operations and contains sixteen digital-to-analog converters even though only four are shown in the two levels of the unit illustrated in FIG. 10. By the interconnection of several digital-to-analog converters and amplifiers many arithmetic operations can be performed. However, with as many as sixteen converters it is unlikely that any particular arithmetic operation would have many applications. Therefore, four multiplexers are connected to the input of each of the first stage digital-to-analog converters 82a, 82b etc. With reference to the first level of the arithmetic unit, the four multiplexers digitally controlling the inputs to converter 82a are designated as 80a, 80b, 80c and 80d, respectively. Furthermore, two multiplexers are connected to the input of each of the second stage converters 84a, 84b etc. Referring again only to the first level of the arithmetic unit, the multiplexers are designated as 90a and 90b. Connected in the output of each level of section I are three multiplexers which in the first level are designated as 94a, 96a and 98a. The purpose of these multiplexers is to re-route the analog signals so that many different arithmetic operations can be performed. In other words, by means of multiplexing, the interconnections of the digital-to-analog converters and analog information sources can be altered, thereby changing the programmed analog arithmetic operations within a few microseconds.

Digital control signals M_1 , M_2 , M_3 and M_4 open and close multiplexers 80a, 80b, 80c and 80d, respectively, in order to gate or block the analog information appearing on the corresponding lines 100a, 100b, 100c and 100d. Input line 100c carries an analog reference voltage of $+U$ having a value of positive unity whereas line 100a carries the analog voltage output from the amplifier 102h (not shown) in level 3, and line 100b carries the analog voltage from amplifier 102g (not shown) in level 7. In-

7 put line 160d may be connected to any desired external source of analog information.

One of the analog inputs passes through one of the selected closed multiplexers 80 to the input of digital-to-analog converter 82a. A digital input D₁ is also applied to converter 82a. The analog output A₁ of converter 82a is applied to a negative summing amplifier 102a which has a gain of -1. The analog output -A₁ of amplifier 102a is then applied to multiplexer 96b which is operated under the control of the digital input N₂. The output 10 side of multiplexer 96b is connected to the input of the converter 84a along with the output side of multiplexer 96a which is digitally controlled by a digital control signal N₁ to gate a -U analog reference signal there through. Note also that the output of amplifier 102a is connected 15 through a multiplexer 104a to the input of converter 82b in the second level of the arithmetic unit.

Also applied to converter 84a is a digital input D₂. The analog output -A₂ of converter 84a is applied to another summing amplifier 106a having a gain of -1. The analog output A₂ of amplifier 106a is connected through multiplexer 96a to the first level output resistor 108a. Ground potential is also connected to output resistor 108a through multiplexer 94a under the control of digital signal V₁. The analog voltage output A₂ from amplifier 106a is also applied along line 110 through an input resistor 112a to provide a current input to another summing amplifier 106b having a gain of -1. Amplifier 106b provides an inverting function so that its output is minus A₂ (-A₂). A₂ may also be selectively switched to output resistor 108a through the multiplexer 98a under the control of a digital control signal S₂. Therefore, depending upon which of the multiplexers 94a, 96a or 98a is closed by its corresponding digital control signal V₁, S₁ or S₂, either ground voltage, analog output voltage A₂ or analog output voltage -A₂, respectively, will be applied to the first level output resistor 108a as analog current signal B₁ which in turn is applied to point 116 which is the output terminal of Section I. Note that the second, third, etc. levels of the arithmetic unit provide corresponding analog signals B₂, P₃ etc. All of which are applied to point 116 at the output of Section I.

Section II of the arithmetic unit comprises a digitally controlled variable gain amplifier 119 of the type illustrated in FIG. 5. The arithmetic unit 150 has only one 45 variable gain amplifier and it comprises a summing amplifier 120 having a gain of -1 and in a feedback loop a digital-to-analog converter 122 which is capable of handling either positive or negative analog quantities. A digital signal F₁ is applied to converter 122 and thereby 50 digitally controls the gain of the amplifier 120. The purpose of the variable gain amplifier is to adjust the gain or amplification of the resultant analog current signal ΣB which is the sum of the analog signals B₁, B₂, B₃ etc. so that the input to Section III is as large as allowable. Such a high gain is desirable because Section III contributes the largest part of the total error so that, if the 55 gain of variable gain amplifier 119 is large, then the relative error due to Section III is small.

The actual conversion of the output of the hybrid arithmetic unit to digital form is performed in Section III. Section III performs one of two functions. Either it converts the value of the input analog signal A₁₇ from amplifier 120 or else it converts the reciprocal thereof. If the input analog voltage A₁₇ is positive, then it is 60 switched through multiplexer 125a under control of the digital signal T₁ and used as a reference voltage for a digital-to-analog converter 123. Negative unity reference voltage -U is switched through multiplexer 125d under the control of digital signal T₄ and used as a reference voltage for a digital-to-analog converter 124. As 65 discussed in connection with FIG. 7, depending on which of the digital inputs F₂ or F₃ to the converters 123, 124, respectively, is preset and which is varied until the input to the comparators are equal, either the function A₁₇ or 70

its reciprocal is digitized. If the analog input A₁₇ is negative then the input would be gated through multiplexer 125c and used as a reference voltage for converter 124 and an analog positive unity reference voltage +U would be switched through multiplexer 125b and used as a reference voltage for converter 123.

Analog output A from converter 123 and analog voltage B from converter 124 are applied as inputs to comparator 126 whose digital output P indicates in binary fashion whether A or B is the larger of the two inputs. P is also applied to controls 153 (FIG. 13) to cause A and B to become equal as described in connection with FIG. 8.

Therefore, it can be seen that Section I performs the arithmetic operation whereas Sections II and III convert the output of Section I into digital form.

In order to illustrate the flexibility of hybrid arithmetic unit 150 shown in FIG. 10, two problems will be set up for solution by this unit. The first problem will be the computation of the first eight terms of a Taylor Series expansion with arbitrary coefficients and the second will be the multiplication of two 8-by-8 matrices.

EXAMPLE 1

Assume that it is desired to calculate e^x for arbitrary values of x. If e^x is expanded in a Taylor Series the result is:

$$(17) \quad e^x = 1 + x + \frac{x^2}{2!} + \cdots + \frac{x^7}{7!}$$

If the proper multiplexers of FIG. 10 are in the 1 state and all others are in the 0 state, the interconnections shown in FIG. 11 would result.

In FIG. 11, the various components are assigned the same reference numerals used in FIG. 10. Since multiplexer 96a gates the negative unity reference voltage -U to the input of converter 84a and the digital input D₂=1, the analog output B₁ from amplifier 106 equals 1·1 or 1 and is switched through multiplexer 96a under control of digital signal S₁ to the output resistor 108 as an analog signal B₁. Analog signals B₂, B₃, etc. representing the second and third terms, etc., respectively, of the Taylor Series are fed through their respective output resistors 108 to the point 116 at the output of Section I.

In the second level of the arithmetic unit 150 shown in FIG. 11, multiplexer 104c under control of digital signal M₇ gates the negative unity voltage -U to the input of converter 82b. The digital input D₃ in this case equals x and, therefore, the output of amplifier 102b is 1·x or x. This output is gated through multiplexer 96d to the input of the converter 84b. Also applied to converter 84b is the digital input D₄ equal to 1, thereby resulting in an analog signal output A₄ from amplifier 106c. Signal A₄ is applied through resistor 112b to amplifier 106d whose function is to invert its input thereby providing through multiplexer 98b an analog output signal B₂ equal to x·1.

The analog output x from amplifier 102b in the second level is also applied as the input to a digital-to-analog converter 82c in the third level. The digital input D₅ to converter 138 is equal to x thereby resulting in an output from amplifier 82c equal to x². The x² analog signal is applied to the input of the converter 84c together with the digital input D₆ equal to 1/2!. Such an arrangement provides an output B₃ equal to

$$x^2 \cdot \frac{1}{2!}$$

from amplifier 106c to the point 116. The voltages represented by B₁, B₂ . . . B₃ are all summed in the common output circuit including resistors 108a, b, c, etc. and applied as a single analog voltage to variable gain amplifier 119 in Section II, the analog output A₁₇ thereof being proportional to

$$1 + x + \frac{x^2}{2!} + \cdots + \frac{x^7}{7!}$$

or e^x to the accuracy of the eight terms of the Taylor Series. This summed voltage can be used as such or else it can be converted to a digital number in Section III which comprises a comparator or digitizing circuit as shown in FIG. 7. If the value of e^x for a different value of x is desired, the coefficients D_2 , D_4 and D_6 , etc. remain the same and x is changed. For large values of x , i.e., x greater than 1, eight terms of the Taylor Series may not be sufficient. For this case additional terms can be calculated separately and the results added.

EXAMPLE 2

The second example is the multiplication of two 8-by-8 matrices. Such an operation may be expressed in equation form as follows:

$$(18) \quad (C) = (A)(B)$$

where

(C) is the product matrix of the multiplication.

(A) is the first 8-by-8 factor matrix comprising 64 terms: a_{11} , a_{12} , a_{13} etc.

(B) is the second 8-by-8 factor matrix comprising 64 terms: b_{11} , b_{12} , b_{13} etc.

(C) comprises 64 terms $C_{11} + C_{12} \dots C_{ij} \dots C_{88}$.

and where C_{ij} , for example, is the product of the i th row of matrix A and the j th column of matrix B and may be expressed as follows:

$$(19) \quad C_{ij} = a_{11} \cdot b_{1j} + a_{12} \cdot b_{2j} + a_{13} \cdot b_{3j} \dots a_{18} \cdot b_{8j}$$

In FIG. 12 the heavy lines show the interconnections of the hybrid arithmetic unit 150 of FIG. 10 for performing such multiplication. The digital input D_1 to the converter 82a is a_{11} where as the analog reference $+U$ is switched through multiplexer 80c under control of digital signal M_3 , thereby making the analog reference voltage A_1 applied to the converter 84a proportional to a_{11} . The digital input D_2 to converter 84a is equal to b_{11} and, therefore, the output B_1 of the first level of Section I unit is an analog voltage proportional to the product $a_{11} \cdot b_{11}$. In a similar manner, B_2 is made proportional to $a_{12} \cdot b_{21}$, etc. The analog voltages B_1 , $B_2 \dots B_8$ are all summed by resistors 108 and applied to summing amplifier 119 of Section II to provide an analog output voltage A_{17} equal to C_{11} which in turn may be digitized in Section III by applying plus unity reference $+U$ through multiplexer 125b to the input of converter 123, switching C_{11} through multiplexer 125c to the input of converter 123, setting the digital input F_3 to a value of 1 and then varying the digital input F_2 to converter 123 until the analog quantities A and B applied to comparator 126 are equal, at which point F_2 represents the value of C_{11} in digital form in a manner explained in connection with FIGS. 7 and 10.

When multiplying two 8-by-8 matrices, sixty-four such multiplications must be performed. In order to obtain the $C_{1(j+1)}$ term, the "a" entries remain the same and only the "b" entries must be changed. In other words, in order to get succeeding C entries only half the information must be changed. Such an arrangement, of course, is time saving. If larger than 8-by-8 matrices are to be multiplied, the computation is done in parts, and the results are added.

Referring once again to FIG. 10, it is to be noted that the signs of the analog outputs B_1 , B_2 , B_3 etc. are controlled by digital means. This control is accomplished by causing digital information to choose the proper channels to be multiplexed together thereby determining the flow of analog information. Such an arrangement, when coupled with the mathematical rules for signs, permits the computation of the sign of each term. For example, in FIG. 10 it can be seen that if multiplexer 96a is closed by digital control signal S_1 and multiplexer 98a remains open, B_1 will be positive. If the reverse is true, B_1 will be negative. The digital logic handling this sign decides whether B_1 should be positive or negative and the digital control signals, S_1 and S_2 , accordingly selects multiplexer

96a or 98a. Of course, the analog signals B_2 , $B_3 \dots B_8$ are all handled in the same manner.

Another important feature of the arithmetic unit shown in FIGS. 10, 11 and 12 is that although only digital inputs were used in Examples 1 and 2, combinations of both digital and analog quantities could be operated on by utilizing the multiplexers 80, 104, etc. to apply analog information, rather than a reference, to converters 82, a , b , etc. Such flexibility is an important feature of the hybrid digital/analog arithmetic unit embodying this invention.

Hybrid arithmetic unit combined with digital computer

15 FIG. 13 is an auxiliary arithmetic unit, A.A.U., of which the hybrid digital analog arithmetic unit, D/A.A.U. 159 shown in FIGS. 10, 11 and 12, is a part.

The inputs to A.A.U. are from two sources. The digital information is from a digital computer (not shown) 20 whereas the analog information is from external analog sources, for example, strain gages, tachometers, thermocouples, pressure gages or any other device whose reading can be more conveniently converted to a voltage rather than directly to a digital quantity. The output is a digital quantity which is the result of the computation and which generally goes back to the computer or possibly to some 25 remote digital-to-analog converter which controls some process by means of a voltage level.

In order to solve problems in the A.A.U. the following chain of events occur:

30 (1) A "Load Information" command comes from the digital computer which tells A.A.U. that operation registers 152 and data registers 154 are to be loaded. (Data registers 154 contain the digital information D_1 , D_2 etc. that sets the converters 82a, b , etc. and 84a, b , etc. in Section I of FIG. 10 and operation registers 152 select the operation or computation.) In order to permit this loading, the information gate associated with these registers is opened by controls 153.

35 (2) The digital information comes from the computer serially by word, each word containing a tag which tells whether it is an operation or data. The word is then gated into the proper register. This process is continued until the operation and all the data is loaded into the proper registers.

40 (3) The "Load Information" line is lowered.

45 (4) The signs ψ of the data D and the operation information M, N, V are applied to a polarity decoder 156. The output S of polarity decoder 156 is applied as the digital control signals S_1 , S_2 , S_3 , S_4 , etc. to multiplexers 96a, b , etc. and 98a, b , etc. of D/A.A.U. 159.

50 (5) The operation information M, N, V is also applied as M_1 , z , etc. N_1 , z , etc. and V_1 , z , etc. digital control signals to the corresponding multiplexers 80, 90, 96, and 98 of D/A.A.U. 159.

55 (6) The digital information D is applied to the appropriate converters 82 and 84 of D/A.A.U. 159.

60 (7) The operation information ϕ which determines whether a function or its reciprocal is desired and therefore helps decide which of digital quantities F_2 or F_3 is preset, is applied to controls 153.

(8) The "Start Computation" command is given.

65 (9) ϕ , the polarity output H, and the digital output P of comparator 126 determine the digital inputs F_1 , F_2 and F_3 in the manner previously described.

70 (10) F_1 is the scaling factor which maintains analog signal A_{17} as near full scale voltage as possible for a desired accuracy as determined by a test cycle in which one of the analog inputs A and B is set at the minimum amplitude and compared with the amplitude of a computed analog signal A_{17} . F_2 or F_3 is the answer depending on both ϕ and the polarity output H which controls the digital switching signals, T_1 , T_2 , etc.

75 Although in FIG. 13 the analog input signals come directly from an external source, they may also come from a bank of multiplexers and amplifiers, in which case, be-

fore every operation, the proper channels are multiplexed on to the external analog information line.

The auxiliary arithmetic unit shown in FIG. 13 performs fixed decimal point operations, and therefore, the decimal point must be considered separately. 5

Conclusions

Since most of the errors are fixed, it is particularly desirable to operate as close to full scale as possible. The variable gain amplifier shown in FIGS. 5, 10, 11 and 12 helps achieve this. Generally speaking, hybrid digital/analog arithmetic will not be useful where accuracy is at a premium, however, there are some problems in which its accuracy is sufficient. In some problems, the accuracy of the information itself is limited so that extreme accuracy of computation is unwarranted. Two examples of this occur in industrial process control and in circuit analysis. In the former the input information is in analog form, and in the latter the most precise components are often 5% resistors. 10

As far as speed of computation is concerned, in hybrid digital/analog arithmetic most operations take the same time, for example, the solution of:

$$(20) \quad y = a + b$$

would take the same time as:

$$(21) \quad y = a_{11} \cdot b_{11} + a_{12} \cdot b_{21} + \dots + a_{18} \cdot b_{81}$$

In one actual test, the average speed of computation for the single addition in the first example was 100 μ sec., whereas the average speed of the eight multiplications and seven additions in the second problem is 6.8 μ sec. per single computation. The latter speed is fast even when compared to high-speed digital arithmetic. Such speeds are considered to be only exemplary, and not limiting, since even higher speeds are obtainable. 20

Another aspect of speed to consider is the number of times memory must be used in the course of computation since in high-speed computation the memory may be the limiting speed factor. Therefore, a less conspicuous advantage of hybrid digital/analog arithmetic is that it requires fewer trips to memory for a computation as compared to digital arithmetic. 25

A third important factor is that during the time the hybrid arithmetic unit is computing, it can operate completely independently of the rest of the computer, thereby allowing the computer to perform its necessary functions in parallel with the hybrid arithmetic unit for most of its cycle. 40

The switches and multiplexers described above and illustrated in the drawings may be, in their simplest form, electromagnet relays, but in order to attain the desirable fast switching, transistors or other semi-conductor devices are preferred.

While there has been shown and described and pointed out the fundamental novel features of the invention as applied to a preferred embodiment, it will be understood that various omissions and substitutions and changes in the form and detail of the device illustrated and in its operation may be made by those skilled in the art without departing from the spirit of the invention. It is the intention, therefore, to be limited only as indicated by the scope of the following claims. 50

What is claimed is:

1. A hybrid arithmetic unit comprising:
  - (a) a first and a second plurality of digital-to-analog converters,
  - (b) means for applying first digital data signals to each of the first plurality of converters,
  - (c) a plurality of analog signal sources,
  - (d) a source of digital control signals,
  - (e) first multiplexer switching means responsive to the digital control signals for applying selected analog

signals to the first plurality of converters, thereby providing at the output of each of the first plurality of converters an analog output signal proportional to the corresponding first digital data signal and selected analog input signal applied thereto,

(f) second multiplexer switching means responsive to the digital control signals for applying the analog output signals to the second plurality of digital-to-analog converters,

(g) means for applying second digital data signals to the second plurality of converters, thereby providing at the output of each of the second plurality of converters a second analog output signal proportional to the corresponding first analog output signal and second digital data signal applied thereto,

(h) inverting means responsive to the digital control signals for inverting the second analog output signals,

(i) circuit means for summing the second analog output signals to produce a resultant analog output signal, and

(j) third switching means responsive to the digital control signals for connecting the second analog output signals to the circuit means.

2. A hybrid arithmetic unit as defined in claim 1 further comprising means connected to the circuit means and responsive to further digital control signals for digitizing the resultant analog signal.

3. A hybrid arithmetic unit as defined in claim 2 wherein the first multiplexer switching means also selectively applies the first analog output signal from one of the first plurality of converters to another of the first plurality of converters. 30

4. In combination:

(a) a digital computer for providing digital data signals and digital control signals,

(b) a plurality of digital-to-analog converters,

(c) first storage register means for receiving the digital data signals from the digital computer and applying them to the inputs of the converters,

(d) a plurality of analog signal sources,

(e) multiplexer switching means responsive to the digital control signals for selectively connecting the analog signal sources to the inputs of the converters,

(f) second storage register means for receiving the digital control signals from the digital computer and applying them to the inputs of the multiplexer switching means, whereby an analog output signal is produced at the output of each of the converters proportional to the product of the applied digital data signal and the selected analog signal,

(g) circuit means connected to all of the converter outputs for summing the analog output signals, thereby providing a resultant analog signal, and

(h) means for digitizing the resultant analog signal in response to the digital control signals. 55
